UNITED STATES PATENT OFFICE.

EMORY LEON CHAFFEE, OF BELMONT, MASSACHUSETTS, ASSIGNOR TO JOHN HAYS HAMMOND, JR., OF GLOUCESTER, MASSACHUSETTS.

MULTIFREQUENCY RESONANT NETWORK.

Application filed March 31, 1922. Serial No. 548,538.

This invention relates to signaling systems and more particularly to such systems employing a plurality of frequencies.

Some of the objects of the present invention are to provide an improved signaling system; to provide improved means for producing simultaneously at least two oscillatory currents of unlike frequencies; to provide means for producing such currents with improved efficiency, and for combining currents of unlike frequencies derived from a plurality of sources and amplifying such currents independently; to provide means for reducing interference between parts of a coupled circuit network; and to provide other improvements as will appear from the following description taken in connection with the accompanying drawings.

Referring to the drawings:

20 Figure 1 shows a portion of a signalling system in which there is produced in a coupled circuit network a plurality of currents of unlike frequencies;

25 Fig. 2 shows a modified form of the system of Figure 1 employing tube generators;

Fig. 3 shows a transmitting station employing the features of the invention and forming part of a radiant energy signalling system;

30 Fig. 4 shows a modified form of the transmitting station of Figure 3, using vacuum tube generators, and

Fig. 5 shows another modification in which oscillatory circuits are excited directly by oscillating tubes.

Referring to the drawings and more particularly to Figure 1, one embodiment of my invention comprises a plurality of sources of alternating current of unlike frequencies, 40 such as alternators 10, 11 each coupled by means of a coil 12, 13 respectively to a pair of power amplifiers 14, 15. Each of these amplifiers consists of a usual, three element vacuum tube having a heated filament 17 forming a hot cathode, a grid 18 for controlling the passage of electrons, and a plate 19 upon which the electrons may impinge.

The circuit of the plate 19 of the amplifier 14 includes a pair of inductances 27 and 25. Similarly the circuit of the plate of the amplifier 15 includes a pair of inductances 26 and 28. The inductances 25 and 26 to-

gether with a third inductance 22 coupled thereto, may be considered as forming windings of a coupler 20. The inductances 27 and 28 together with an inductance 23 coupled thereto, may also be considered as forming windings of a coupler 21. The couplers 20 and 21 have preferably substantially equivalent magnetic and structural characteristics. The windings 22 and 23 are coupled together by means of a coupling which may take any desired form of inductive, capacitative or resistance coupling, that shown being an inductive coupling 24 of conventional type. Suitable condensers 29 and 30 and resistance coils 31 and 32 are included in the connections to the coupling 24.

The connections of the windings 25, 27, which are in series, are such as to produce induced currents in the windings 22, 23 of the couplers 20, 21 having predetermined relative polarities. The connections of the winding 28 are similar thereto, and produce with like primary increase or decrease, 70 a secondary current in the winding 23 having the same polarity as in the previous case. The connections of the winding 26 are reversed with respect thereto so that with a like primary increase or decrease a 75 current of opposite polarity is produced in the winding 22.

The circuit comprising the winding 22, condenser 29, etc. is designated 33, and the circuit comprising the winding 23, condenser 30, etc. is designated 34. The circuits 33 and 34 are arranged so that their inductance and capacity constants and the characteristics of the coupling coil 24 cause them to be resonant to the frequencies of both 80 currents produced by the alternators 10 and 11. When currents of these selected frequencies co-exist in these coupled circuits, then for one of these frequencies the currents in both parts are very closely in phase 85 and for the other frequency they are very closely opposite in phase. Thus if for the frequency of the current produced by the source 10 the current in the circuit 33 is at a given moment flowing in the direction indicated by the arrow 35 at its maximum positive value, there will be for a certain connection of the coupling 24 a current flowing 90 in the circuit 34 in the direction indicated 95 100

by the arrow 36 at maximum positive value, at the same moment. For the frequency of current produced by the source 11, however, when the induced current is a maximum positive in circuit 33 as indicated by the arrow 37, it will be substantially a maximum negative in circuit 34, that is, the direction of current will be as indicated by the arrow 38. This property is not confined to networks of the specific form illustrated, but is common to many if not all circuits which have two natural periods of oscillation, sometimes designated two degrees of freedom.

The energy imparted to the coupled circuits 33 and 34 through the windings 25 and 27 from the amplifier 14, consisting of electric waves of one of the selected frequencies to which the circuit networks 33 and 34 are resonant, is transmitted thereto freely. Let it be assumed that at a given moment the currents are flowing in the direction indicated by the arrows 35, 36. The couplings provided to the amplifier 15 by the windings 26, 28 are so connected, however, that waves of the frequency delivered from the amplifier 14 do not appear in the plate circuit of the amplifier 15, the windings 26, 28 being connected so that these currents oppose each other. On the other hand, the energy imparted to the coupled circuits 33 and 34 through the windings 26 and 28 from the amplifier 15, consisting of electric waves of one of the selected frequencies to which these circuits are resonant, is transmitted thereto freely. The direction of the currents of this different frequency is as indicated by the arrows 37, 38 respectively, and since the connections of the windings 25, 27 are as previously described, the effects of these waves in the plate circuit of the amplifier 14 are substantially neutralized.

Thus it will be seen that substantially no interaction between the sources is produced, and that the respective power amplifiers operate independently of each other, so that neither is subjected to currents of any frequency other than that which it is intended shall be amplified by it. This condition of having only a single frequency to amplify is the condition under which a high efficiency, that is a high ratio of output energy to input energy, is obtained, with amplifying devices of this character, and this constitutes an important feature of my invention. Accordingly amplifier tubes 14, 15 of relatively great power can be employed efficiently.

Referring to Figure 2 there is provided the same circuit network 33, 34 as in the previous case, the current supply to the inductive couplings 12 and 13 being obtained from a corresponding number of vacuum tube generators, such as 50, 51. Each of these includes a three-element vacuum tube, such as

52, of conventional type, and a coupling 53 whereby the plate circuit is coupled back to the grid circuit and regenerative oscillations are obtained continuously.

The operation of the system of Figure 2 is similar to that described for Figure 1, with the exception that sources 50, 51 provide the energy used.

Referring to Figure 3, a transmitting station comprising the features of the invention includes a transmitting antenna 101 connected to earth 102 through the circuit 34 of the coupled network 33, 34, corresponding to the coupled network 33, 34 of Figure 1. A pair of sources of alternating current 80 of unlike frequencies, such as alternators 110, 111 are inductively coupled by means of a pair of couplers 112, 113, respectively, to a pair of power amplifiers 114, 115. The circuit 116 and its operations is substantially the same as that of network 16 of Figure 1, like parts being designated by numerals having corresponding tens and units digits.

Thus in a manner similar to that described in detail for Figure 1, energy is transmitted to the coupled network 33, 34 from a plurality of sources of alternating currents of unlike frequencies independently, and each of these currents may be amplified by means 90 of amplifiers of relatively high power, and at a great efficiency.

Referring in detail to Figure 4, this shows a transmitting station corresponding to the transmitting station of Figure 3, excepting that in place of the alternators 110, 111 there is provided a plurality of sources of current, such as 150, 151 each including an oscillating vacuum tube 152. These are the same as in Figure 2, like parts being designated 100 by reference characters having like tens and units numerals. The arrangement is such that the oscillator 151 produces a frequency 105 different from that produced by the oscillator 150. 110

It is obvious that the transmitting stations of Figures 3 and 4 may be employed as parts of systems for communication through the ether. Messages may be transmitted in any suitable manner, as for example, by interrupting one or more of the sources of current. 115

The modified embodiment of the invention shown in Figure 5 comprises a circuit network 33, 34 as in Figure 2, the oscillatory 120 circuits of the network being excited directly by a pair of vacuum tubes 60 and 61. A coupling 62 is provided for inductively coupling the plate and grid circuits of the tube 60 to each other and to the inductances 25 125 and 27. Thus the tube 60 is connected for feeding back energy from its output to its input circuit, and the regenerative oscillations thereby produced are impressed upon the circuit network 33, 34 in the same man- 130

ner as was described previously in connection with Figures 1 and 2. Similarly, a coupling 63 is provided for inductively coupling the plate and grid circuits of the tube 5 61 to each other and to inductances 26 and 28. The regenerative oscillations thus produced are impressed upon the circuit network 33, 34 in the same manner as described in connection with the corresponding inductances 26 and 28 of Figure 1.

Suitable means such as a tuning condenser 64 may be provided for determining the frequency of current produced by the tube 60 and its associated couplings; and a 15 similar means such as a condenser 65 is provided for the tube 61 and its associated couplings. The condenser 65 is adjusted to a different value from that of the condenser 64, so that currents of relatively different 20 frequencies are produced.

The operation of the system of Figure 5, will be obvious from the foregoing description taken in connection with the description of the operation of Figure 2. It will be 25 seen that oscillatory currents of unlike frequencies are produced, and these are independently impressed upon the network 33, 34, and allowed to coexist therein, their values being coincident respectively with 30 the two natural frequencies of the coupled network 33, 34.

Thus it will be seen that I have provided a simple and economical means for independently generating two currents and applying them to a single network without having either current affect the generation of the other current. By this means substantially no reaction on either source of current exists due to the generation of current by the other source.

Furthermore, two sources of alternating currents of different frequencies may readily and efficiently be held at constant difference, that is, although their periodicities 45 may vary slightly due to unavoidable variations in the operation of the sources, the difference may be held substantially constant.

It is to be noted that in the embodiments 50 of Figures 3 and 4, the amplitude of the combined currents of different frequencies is at a minimum in circuit 33 when it is at a maximum in circuit 34 and vice versa. Accordingly the point of energy dissipation 55 is shifted from one portion (33) of the coupled network to the other portion (34) alternately, the action of the energy sources remaining substantially constant.

The construction illustrated and described herein is merely what I now consider to be the preferred embodiment of my invention and it is therefore to be distinctly understood that I do not limit myself thereto as many changes may be made in point 60 of detail and other embodiments resorted

to without deviating from the true spirit and scope of my invention as defined by the appended claims.

Having thus described my invention, what is claimed is:

1. A system for the production of oscillatory energy comprising a circuit network, means for impressing upon said network at a pair of spaced portions thereof a pair of substantially synchronous, oscillating, electro-motive forces of substantially equal value and mutually aiding, and means for impressing upon said network at a pair of spaced portions thereof a second pair of substantially synchronous, oscillating, electro-motive forces of substantially equal value and opposing one another. 70

2. A system for the production of oscillatory energy comprising a circuit network, means comprising a regenerative vacuum tube for impressing upon said network at a pair of spaced portions thereof a pair of substantially synchronous, oscillating, electro-motive forces of substantially equal value and mutually aiding, and means comprising a regenerative vacuum tube for impressing upon said network at a pair of spaced portions thereof and in opposite relations a second pair of substantially synchronous, oscillating, electro-motive forces of substantially equal value and of a frequency different from that of the first-mentioned electro-motive forces. 85

3. A system for the production of oscillatory energy comprising a circuit network, a three-electrode, electron emitting device, means for coupling the output circuit of said device to said network at a pair of spaced portions thereof in a manner to impress thereon a pair of substantially synchronous, oscillating, electro-motive forces of substantially equal value and mutually aiding, a second three-electrode, electron emitting device, and means for coupling the output circuit of said second device to said network at a pair of spaced portions thereof in a manner to impress thereon a second pair of oscillating, electro-motive forces of substantially equal value and opposing one another. 100

4. A system for the production of oscillatory energy comprising a circuit network, means comprising an electron emitting device connected for continuous regeneration and an amplifier for amplifying the currents produced by said regeneration for impressing upon said network at a pair of spaced portions thereof a pair of substantially synchronous, oscillating, electro-motive forces of substantially equal value and mutually aiding, and means comprising an electron emitting device connected for continuous regeneration and an amplifier for amplifying the currents produced by said regeneration for impressing upon said network. 110

work at a pair of spaced portions thereof a second pair of oscillating electro-motive forces of substantially equal value and opposing one another.

- 5 5. A system for the production of oscillatory energy comprising a circuit network including two, inter-coupled circuits each having inductance and capacity, means comprising a three-electrode, electron emitting device and like couplings between the output circuit of said device and the network for impressing upon said network at a pair of spaced portions thereof a pair of substantially synchronous, oscillating electro-motive forces of substantially equal value and mutually aiding, and means comprising a second, three-electrode electron emitting device and reversely-arranged couplings between the output circuit of said second device and the network for impressing upon said network at a pair of spaced portions thereof and in opposite phase relations a second pair of oscillating electro-motive forces of substantially equal value and of a frequency different from that of the first mentioned electro-motive forces.

6. A system for the production of oscillatory energy comprising a circuit network, means comprising an electron emitting device connected for producing oscillations of a predetermined frequency and a second electron emitting device for amplifying the currents produced by said device for impressing upon said network at a pair of spaced portions thereof a pair of substantially synchronous oscillating electro-motive forces of substantially equal value and mutually aiding, and means comprising a third electron emitting device connected for continuously producing oscillations of a relatively different frequency, and an additional electron emitting device for amplifying the currents produced by said third named electron device for impressing upon said network at a pair of spaced portions thereof a second pair of oscillating electro-motive forces of substantially equal value and opposing one another.

7. Apparatus for producing oscillating current comprising a plurality of couplers each having a plurality of windings, a source of oscillating current of a predetermined frequency, an amplifier for amplifying said current, said source and amplifier being operatively connected to a winding of each of the couplers, a second source of oscillating current of relatively different frequency, a second amplifier for amplifying said second current, said second source and second amplifier being operatively connected to a second winding of each of the couplers, and a network composed of inter-coupled circuits and including a third winding of each of the couplers, the connections of at least one of the windings of one of the cou-

plers being unlike the connections of the corresponding winding of the other coupler.

8. Apparatus for producing oscillating current comprising a plurality of couplers each having a plurality of windings, a source of periodic impulses of a predetermined frequency, an amplifier for amplifying said impulses, said source and amplifier being operatively connected to a winding of each of the couplers, a second source of periodic impulses of relatively different frequency, a second amplifier for amplifying said second named series of impulses, said second source and second amplifier being operatively connected to a second winding of each of the couplers, a network composed of two, inter-coupled circuits and including a third winding of each of the couplers, the connections of one of the first named windings of one of said couplers being reverse with respect to the connections of the corresponding winding in the other coupler.

9. A system for transmitting radiant energy comprising a circuit network resonant to currents of two frequencies and including two, inter-coupled circuits each having inductance and capacity, means for impressing upon the network at two portions thereof spaced apart substantially synchronous, alternating, electro-motive forces of one of said frequencies, the instantaneous values of the currents produced in the respective portions of the network by said electro-motive force being substantially equal and of like phase, and means for impressing upon the network at two spaced portions thereof additional substantially synchronous, alternating, electro-motive forces of the other of said frequencies, the instantaneous values of the currents produced in the respective portions of the network by said second named electro-motive forces being substantially equal and opposing.

10. A system for transmitting radiant energy comprising a circuit network resonant to currents of two frequencies, means including a three-electrode vacuum tube for impressing upon the network at two portions thereof spaced apart periodically varying electro-motive forces, the instantaneous values of the currents produced in the respective portions of the network by said electro-motive forces being substantially equal and aiding, and means including a three-electrode vacuum tube for impressing upon the network at two spaced portions additional periodically varying electro-motive forces having a relatively different frequency, the instantaneous values of the currents produced in the respective portions of the network by said second named electro-motive force being substantially equal and opposing.

11. A system for producing oscillatory energy comprising a plurality of sources of

periodic impulses of unlike frequencies, a network resonant to said frequencies, and means for coupling the network to said sources constructed to prevent current impulses of one of said frequencies from reacting upon the source of impulses of another of said frequencies.

12. A system for transmitting radiant energy comprising two sources of periodic impulses of different frequencies respectively, a circuit network resonant to both of said frequencies, and means for impressing said impulses upon the network, including couplings reversely arranged to prevent current impulses of one of said frequencies from reacting on the source of impulses of the other of said frequencies.

13. A system for transmitting radiant energy comprising a plurality of sources of periodic impulses of unlike frequencies, a circuit network resonant to a plurality of frequencies and means for impressing said impulses upon the network comprising reversely arranged inductive couplings preventing current impulses of one of said frequencies from reacting through the network upon a source of impulses of another of said frequencies.

14. A system for transmitting radiant energy comprising two sources of periodic impulses of unlike frequencies, a circuit network resonant to both of said frequencies and including two inter-coupled circuits each having inductance and capacity, means for impressing said impulses upon the network comprising reversely arranged couplings for preventing current impulses of one of said frequencies from reacting upon the source of impulses of the other of said frequencies, and means operatively connected with the network for impressing energy upon the ether.

15. A system for transmitting radiant energy comprising a pair of sources of alternating currents of unlike frequencies, a circuit network comprising a pair of coupled oscillatory circuits, and reversely arranged couplings for impressing said currents upon the network so as to substantially neutralize the tendency for one of said currents to react through the net work on the source of current of different frequency.

16. A system for producing oscillatory currents for systems of communication comprising a circuit network including two, inter-coupled circuits each having inductance and capacity, means for impressing upon said network at different portions thereof two substantially synchronous oscillating electro-motive forces of substantially equal value, and means for impressing upon said network at two other different portions thereof a second pair of oscillating electro-motive forces of substantially equal value, the phase relationship between said pairs of

electromotive forces being such that energy is impressed alternately upon the two different portions of the net work.

17. A system for the production of oscillatory energy comprising a circuit network including two inter-coupled circuits each having inductance and capacity, means for impressing upon said network at two spaced portions thereof substantially synchronous, oscillating, electro-motive forces of substantially equal value and like phase, and means for impressing upon said network at two spaced portions thereof and in opposite phase relations two substantially synchronous, oscillating, electro-motive forces of substantially equal value and of a frequency different from that of the first-mentioned electro-motive forces.

18. A system for the production of oscillatory energy comprising a circuit network including two inter-coupled circuits each having inductance and capacity and one of said circuits containing an antenna and ground, means for impressing upon said network at two spaced portions thereof substantially synchronous oscillating electro-motive forces of substantially equal value and like phase, and means for impressing upon said network at two spaced portions thereof and in opposite phase relations two substantially synchronous oscillating electro-motive forces of substantially equal value and of a frequency different from that of the first-mentioned electro-motive forces.

19. A system for the production of oscillatory energy comprising a circuit network including two circuits inductively coupled together and each containing inductance and capacity, means for impressing upon said network at two spaced portions thereof substantially synchronous oscillating electro-motive forces of substantially equal value and like phase, and means for impressing upon said network at two spaced portions thereof and in opposite phase relations two substantially synchronous oscillating electro-motive forces of substantially equal value and of a frequency different from that of the first-mentioned electro-motive forces.

20. A system for the production of oscillatory energy comprising a circuit network including two inter-coupled circuits each having inductance and capacity, means for impressing upon said network at two spaced portions thereof substantially synchronous oscillating electro-motive forces of substantially equal value and like phase, means for impressing upon said network at two spaced portions thereof and in opposite phase relations two substantially synchronous oscillating electro-motive forces of substantially equal value and of a frequency different from that of the first-mentioned electro-motive forces, and means connected with said network for radiating energy into the ether.

21. A system for the production of oscillatory energy comprising a plurality of sources of electro-motive force of different frequencies respectively, a circuit network resonant to currents of a plurality of said frequencies and comprising two, inter-coupled circuits each having inductance and capacity and one containing an antenna and ground, means for impressing upon said network at two spaced portions thereof and from one of said sources substantially synchronous, oscillating, electro-motive forces of substantially equal value and like phase, and means for impressing upon said network at two spaced portions thereof and in opposite phase relations two substantially synchronous, oscillating electro-motive forces from another of said sources and of substantially equal value.
22. A system for the production of oscillatory energy comprising two sources of electro-motive force of two different frequencies respectively, a circuit network resonant to currents of said two frequencies and comprising two inter-coupled circuits, means for impressing upon said network at two spaced portions thereof and from one of said sources substantially synchronous, oscillating, electro-motive forces of substantially equal value and like phase, and means for impressing upon said network at two spaced portions thereof and in opposite phase relation two, substantially synchronous, oscillating, electro-motive forces from another of said sources and of substantially equal value.

In testimony whereof I hereunto affix my signature.

EMORY LEON CHAFFEE.
